UNITED STATES PATENT OFFICE

HARRY R. BALLOU, OF CANTON, OHIO, ASSIGNOR TO THE HOOVER COMPANY, A CORPORATION OF OHIO

SUCTION CLEANER

Application filed February 28, 1929. Serial No. 343,502.

This invention relates to suction cleaners and it particularly relates to means for securing a dust bag to the handle of a suction cleaner.

5 Flexible or expandible means for yieldingly securing the upper end of a dust bag to a suction cleaner handle is relatively well known in the art. These suspension means however, consist primarily in the use of an

10 ordinary helical spring which renders sufficient flexibility for ordinary purposes. These devices provide various degrees of tension on the bag depending upon the angle at which the handle is maintained during the raising and lowering of the same in operating the cleaner.

15 During normal operating conditions the longitudinal axis of the bag is substantially parallel with the suction sweeper handle and in raising the handle upwardly, or when the suction cleaner is to be stored away, the handle is maintained at a substantially vertical position which is usually perpendicular to the horizontal axial center line of the suction cleaner.

20 The ordinary spring suspension means provides a tension and causes a pull to be exerted at the bottom of the bag where the bag mouth is attached to the discharge outlet of the cleaner. Due to this tension and to creasing at the mouth of the bag, caused

25 by manipulation of the handle, the bag will wear out, and dust, which is collected in the bag, will be forced through the bag at the lower end of the neck. While it is desirable,

30 and usually necessary, that a slight tension be maintained on the bag at all times, excess tension caused by raising or lowering the handle will cause the bag to deteriorate and wear out at a rapid rate.

35 The present invention overcomes the disadvantages inherent to the conventional type of suspension means and its primary object is to provide bag suspension means which will provide the same relative tension on the bag

40 regardless of the position of the suction cleaner handle.

45 Another object of the invention is to provide bag suspension means which is connected to the handle of a suction cleaner and which

a pivot to provide an equal tension on the bag at all times.

50 Another object of the invention is to provide bag suspension means which is relatively simple and efficient in operation, which is 55 rigid and substantial in construction, which may be readily and economically manufactured, and which can be easily and quickly applied to existing handles.

55 In accordance with the invention, the suspension means comprises a pivotal rigid member having an outwardly extending arm. A spring is secured to a piece of flexible material, which is also secured to the arm so that tension on one end of the arm will cause it to 60 move on its pivot and provide a compensating effect to offset the tension on the spring and thereby obtain substantially the same tension on the bag regardless of the angle at which the cleaner handle is placed. 70

65 In the accompanying drawing illustrating a selected embodiment of the invention, the views are as follows:

70 Fig. 1 is a side elevation of an electric suction cleaner and embodying the invention. 75

Fig. 2 is an enlarged detail sectional view showing the invention applied to the handle of a cleaner.

Fig. 3 is a transverse sectional view on the line 3, 3 of Fig. 2. 80

Fig. 4 is a detail bottom plan view of the device shown in Fig. 2.

85 Referring to the drawing, 5 designates a suction cleaner generally, which is provided with a discharge neck 6 to which a dust bag 7 is secured. The upper end of the dust bag is secured to the cleaner propelling handle 8 by means of the improved suspension means which is designated generally as 9.

90 The suspension means 9 comprises a plate, or other rigid member 10, which may be secured on the inside of the tubular handle 8. A frame or other suitable support 11 is secured to the handle and carries an arm 12 which is pivoted thereto at 13. A helical tension spring 14 has one end thereof secured to a lug 15 struck up from the plate 10, and its other end secured to a flexible member such as webbing, leather, or other material 16 which passes over the heel 17 of the arm 100

50 has a part thereof which is movable about

12. This webbing is also connected to the arm by means of a plate, or other attachment 18, and extends beyond the end of the arm 12 and provides a flexible attaching 5 portion for engagement with a bag clip or clamping means.

The heel 17 is curved to present a cam surface for engagement by the flexible member 16, the radial distance of such surface 10 from the pivotal axis gradually decreasing in one direction so that, as the arm 12 moves away from the handle 8 and the spring 14 is elongated and its tension thereby increased, the effective radial distance at which the ten- 15 sion of the spring is applied to the arm 12 is lessened. Also, as the handle is raised and the arm 12 swings away from the handle, the direct line between the outer end of the arm 12 and the point of attachment of 20 the lower end of the bag moves outwardly from the pivot 13 so that the effective lever arm of the outer portion of the arm 12 is increased.

Upon upward movement of the handle 8, 25 the arm 12 is swung outwardly and downwardly on its pivot by reason of its connection to the bag 7 through the connecting member 19, such movement of the arm 12 being opposed by the spring 14. During the 30 first part of such movement the rate of angular movement of the arm is comparatively great as compared with that during the latter part of its movement, and the rate of change of the effective lever arm of the outer 35 portion of the arm 12 is comparatively small. Raising of the handle therefore causes greater swinging movement of the arm 12 and overcomes the increased tension on the spring to cause an equal tension to be applied on the 40 bag regardless of the position of the handle. The greatest tendency to increase the tension or pulling power is usually when the bag and handle are in vertical or storing position. This movement therefore causes the arm to 45 swing to the position shown in broken lines in Figure 2 and the lessened effective radial distance of the point of application of the tension of the spring overcomes or compensates for the increased spring pressure and 50 provides the same relatively slight tension, which is desirable.

The invention provides bag suspending 55 means which is comparatively simple and efficient in operation, which provides an equal tension on the bag at all times to eliminate undue wear and tear on the bag normally caused by vertical movement of the handle, and which can be economically manufactured.

Changes may be made in the form, construction and arrangement of the parts without departing from the spirit of the invention, or sacrificing any of the advantages 65 thereof, and the right is hereby reserved to

make all such changes as fairly fall within the scope of the following claims.

I claim:

1. The combination of a hand propelled tool, a handle pivotally mounted on said tool, a container attached to said tool at a point removed from the pivotal axis of said handle, and yielding means for supporting the upper portion of said container from said handle, comprising an arm pivotally carried by said handle at its lower side and connected to the upper end of said container and a spring co-operating with said arm to swing it upwardly toward said handle. 70 75

2. The combination of a hand propelled tool, a hollow handle pivotally mounted on said tool, and having an opening therein, a member attached to said tool at a point removed from the pivotal axis of said handle, and yielding means for supporting the upper portion of said member from said handle, comprising an arm pivotally carried by said handle and extending through the opening therein, said arm being connected to said member and located on the same side of said handle as is the point at which said member is attached to said tool, and a spring within said handle and operatively connected with said arm. 80 85 90

3. The combination of a hand propelled tool, a handle pivotally mounted on said tool, a container attached to said tool at a point removed from the pivotal axis of said handle, and yielding means for supporting the upper portion of said container from said handle, comprising a lever pivotally carried by said handle and having one end thereof connected to said container, and having a series of lever arms successively decreasing in effective length, and a spring secured to said handle and cooperating with said lever arms successively as said lever is moved away from said handle in different position of said lever. 95 100 105

4. The combination of a hand propelled tool, a handle pivotally mounted on said tool, a member attached to said tool at a point removed from the pivotal axis of said handle, and yielding means for supporting the upper portion of said member from said handle, comprising a lever pivotally carried by said handle and having one end thereof connected to said member, a tension spring secured at one end to said handle, the other end of said lever having a curved surface of gradually increasing radius from the pivot point of the lever, and a flexible member connecting the other end of said spring and said lever and contacting with said surface to apply the force of said spring at different effective radial distances from the pivot point of said lever. 110 115 120 125

5. The combination of a hand propelled device, a handle pivotally connected to said device, a container secured to said device at 130

a point offset from the pivotal axis of said handle, and yielding means for supporting said container from said handle, comprising a lever pivoted to said handle, and having 5 one end thereof connected to said container, the other end of said lever having portions of varying radius, and a spring cooperating with said portions of varying radius of said lever successively to apply different rotative 10 forces upon said lever at different angular positions thereof.

6. The combination of a suction cleaner, a handle pivotally mounted on said cleaner, a dust bag connected at its lower end to said 15 cleaner at a point offset from the pivotal axis of said handle, and yielding means for supporting the upper portion of said bag from said handle and maintaining a substantially uniform tension upon said bag, comprising a 20 lever pivotally carried by said handle and having one end connected to said bag, said lever having a series of lever arms varying successively in effective length and a spring 25 cooperating with said lever arms successively at different positions of said lever.

7. The combination of a hand propelled tool, a hollow handle pivotally mounted on said tool and having an opening therein, a member attached to said tool at a point removed 30 from the pivotal axis of said handle, and yielding means for supporting a portion of said member from said handle, comprising a plate, a lever pivotally carried by said plate, a spring carried by said plate and cooperating with said lever to swing it in one 35 direction, and means for connecting said lever and said member, said plate with said lever and said spring being attachable as a unit to said handle adjacent the opening 40 therein.

8. The combination of a hand propelled tool, a hollow handle pivotally mounted on said tool and having an opening therein, a member attached to said tool at a point removed 45 from the pivotal axis of said handle, and yielding means for supporting a portion of said member from said handle, comprising a plate, a spring carried by said plate, and an arm pivotally mounted on said plate and 50 operatively connected to said spring and adapted to be connected to said member, said plate being secured within said handle with said arm extending through said opening whereby said spring is housed within said 55 handle.

9. The combination of a hand propelled device, a handle pivotally mounted on said device, a member attached to said device, and means for supporting the upper portion of 60 said member from said handle, comprising a lever pivoted at a point intermediate its ends and carried by said handle, a spring carried by said handle, and a flexible member for connecting said spring and said member and engaging and secured to said lever.

10. The combination of a hand propelled device, a hollow handle pivotally mounted on said device and having an opening in the lower side thereof, a member attached to said device and extending along said handle, and means for supporting the upper portion of said member from said handle, comprising a lever pivoted at a point intermediate its 70 ends and carried by said handle so as to extend through said opening, a tension spring carried by said handle, and means operatively connecting said spring to the inner end of said lever to swing the outer end of said lever upwardly into close engagement with the outside of said handle.

11. The combination of a hand propelled tool, a handle pivotally mounted on said tool, a container attached to said tool at a point removed from the pivotal axis of said handle and extending along said handle, and yielding means connecting the upper portion of said container and said handle comprising a spring mounted on said handle, a member connected to said container and operatively connected to said spring, and means for varying the application of the force of said spring to said member to maintain substantially the same tension on said container in various positions of said handle.

12. The combination of a hand propelled tool, a handle pivotally mounted on said tool, a member attached to said tool and extending along said handle, and means supporting the upper portion of said member from said handle comprising a lever pivotally carried by said handle and connected to said member, said lever having a surface providing a series of lever arms successively decreasing in effective length, a spring, and means operatively associating said spring with said lever arms successively, the effective lever arms of the points of application of the force of said spring to said lever and to said member by said lever being such as to maintain substantially uniform longitudinal tension upon said member in various positions of said handle.

Signed at Canton, in the county of Stark, and State of Ohio, this 21st day of February, A. D. 1929.
